RAILWAY SIGNALING

Henry S. Young, Wilkinsburg, Pa., assignor to
 The Union Switch & Signal Company, Swiss-
 vale, Pa., a corporation of Pennsylvania

Application February 27, 1936, Serial No. 66,002
 Renewed May 28, 1938

22 Claims. (Cl. 246—50)

My invention relates to railway signaling, and particularly to signaling involving wayside signals located along a trackway for governing the passage of trains.

5 A feature of my invention is the provision of novel and improved apparatus which requires but two line control wires or conductors for establishing a distinctive control for each of three sections in the rear of an occupied section. Each 10 distinctive control is effective to cause a corresponding aspect of the associated wayside signal, whereby there is produced a three-block, four-indication, system of signaling. Another feature of my invention is the provision of apparatus, 15 utilizing asymmetric units, for controlling wayside signals in such a manner as to prevent the display of a less restrictive indication in the event such asymmetric units fail to function properly.

20 I will describe several forms of apparatus embodying my invention, and will then point out the novel features thereof in claims.

In the accompanying drawings, Figs. 1A and 1B are diagrammatic views which, when placed 25 end to end in the order named, illustrate one form of apparatus embodying my invention. Figs. 2 and 3 are diagrammatic views illustrating modifications of a portion of the apparatus shown in Fig. 1A and each also embodying my invention.

Similar reference characters refer to similar parts in each of the several views.

Referring first to Figs. 1A and 1B, the reference characters 8 and 9 designate the rails of 30 a stretch of railway track along which traffic normally moves in the direction indicated by the arrows. These rails are divided by insulated joints 14 into a plurality of track sections or blocks W—X, X—Y, and Y—Z.

40 Each track section is divided by insulated joints 14 into at least two subsections 1T, 2T, 3T, 4T, etc. Each subsection is provided with a track circuit which includes a track battery 15 connected across the rails at one end of the subsection and a track relay, designated by the reference character TR with a prefix the same as the numerical prefix in the reference character of the associated subsection, connected across the rails at the other end of the subsection.

50 To govern the passage of trains through the stretch of railway, a wayside signal, designated by the reference character S with a suitable distinguishing prefix, is provided for each track section. Each of these signals comprises a top unit 55 T and a lower unit L. These units may take any

one of several forms of signal mechanisms such as searchlight, semaphore, color light, or position light. As here shown, each top unit is a color light signal comprising a green, a yellow, and a red lamp; and each lower unit is a color light signal comprising a green and a red lamp.

Each signal is provided with a pair of polarized line control relays designated by the reference characters HR and DR, respectively, each with a prefix the same as the prefix in the reference 10 character of the associated signal.

The relays HR and DR of each signal are connected across the conductors of a two-wire line circuit extending to the signal next in advance. Each relay HR is provided with a shunt including an asymmetric unit A2, while each relay DR is provided with a shunt including an asymmetric unit A3. The units A2 and A3 are oppositely disposed so that current of one polarity but not the other is forced to flow through relay HR, while 20 current of the second polarity but not the first is forced to flow through relay DR. In the arrangement shown herein, relay HR is provided with an additional asymmetric unit A which freely passes the current which is forced by unit 25 A2 to flow through relay HR, but opposes the passage of the flow of current of the other polarity in relay HR. Relay DR is similarly provided with an additional unit A1 which freely passes current that is forced by unit A3 to flow through 30 the relay DR, but opposes the passage of current of the other polarity.

Each signal is provided with a device, designated by the reference character CT with a prefix the same as the prefix in the reference character 35 of the associated signal, for converting into alternating current direct current supplied from a customary source. The devices CT are here shown diagrammatically and may be the well-known current coding relays. Since the particular form of coding relay is not involved in my invention, it will be sufficient to state that each relay CT, when energized, is caused to move its contacts between the front and back points a fixed and definite number of times per minute. 45 Each coding relay has its contacts connected, in the form of a pole changer, to the terminals B and C of the source of direct current at the associated signal so that when the coding relay is operating, the line circuit for the signal next in 50 rear may be supplied with alternating current having a definite frequency. Each coding relay CT is controlled by the relays HR and DR of the associated signal in such a manner that the alternator or coding relay operates only when the 55

associated signal is displaying the two less restrictive indications, that is, when the signal is displaying the "proceed at normal speed" indication, or the "approach next signal at medium speed" indication.

Each signal is provided with a transfer relay designated by the reference character PC with a prefix the same as the prefix in the reference character of the associated signal. Each relay 10 PC is controlled by the associated HR and DR relays and connects the line circuit for the signal next in rear, either with the pole-changing contacts of the associated coding relay CT to supply alternating current to that line circuit, or with 15 contacts of the associated HR and DR relays to supply direct current to that line circuit.

Each of the color light signals herein shown is controlled by the associated relays HR and DR in the following manner: When both relays are deenergized (see signal 13S), the red lamp R of the top unit T is lighted by a circuit which passes from terminal B of a suitable source of direct current energy through back point of contact 16 of relay 13DR, back point 17 of relay 13HR, and 20 lamp R to terminal C of the same source of energy; and the red lamp R of the lower unit L is lighted by a circuit which passes from terminal B through back point of contact 18 of relay 13DR and lamp R to terminal C. Signal 25 13S, therefore, displays a red light over a red light to indicate "stop". When relay HR is energized and relay DR is deenergized (see signal 12S), the yellow lamp Y of the top unit T is lighted by a circuit which passes from terminal 30 B through back point of contact 19 of relay 12DR, front point of contact 20 of relay 12HR, and lamp Y to terminal C; the red lamp R of the lower unit L is lighted by a circuit which passes from terminal B over back point of contact 35 21 of relay 12DR and lamp R to terminal C. Signal 12S, therefore, displays a yellow light above a red light to indicate "approach next signal prepared to stop". When relay HR is deenergized and relay DR is energized (see signal 11S), 40 the yellow lamp Y of the top unit T is lighted by a circuit which passes from terminal B through front point of contact 22 of relay 11DR, normal polar contact 23-24 of relay 11DR, back point of contact 25 of relay 11HR, and lamp Y to 45 terminal C; and the green lamp G of the lower unit L is lighted by a circuit which passes from terminal B through front point of contact 26 of relay 11DR, normal polar contact 27-28 of relay 11DR, back point of contact 29 of relay 11HR, and lamp G to 50 terminal C. Signal 11S, therefore, displays a yellow light above a green light to indicate "approach next signal at medium speed". When both relays HR and DR are energized (see signal 10S), the green lamp G of the 55 top unit T is lighted by a circuit which passes from terminal B through front point of contact 31 of relay 10DR, normal polar contact 32-33 of relay 10DR, front point of contact 34 of relay 10HR, normal polar contact 35-36 of relay 60 10HR, and lamp G to terminal C; and the red lamp R of the lower unit L is lighted by a circuit which passes from terminal B through front point of contact 37 of relay 10DR, normal polar contact 38-39 of relay 10DR, front point of 65 contact 40 of relay 10HR, and lamp R to terminal C. Signal 10S, therefore, displays a green light over a red light to indicate "proceed at normal speed".

As shown in the drawings, the section immediately to the right of point Z is occupied by a

train K, so that the line circuit for that section is opened with the result both relays 13HR and 13DR are deenergized.

When both relays 13HR and 13DR are deenergized, relay 12HR is energized by direct current of one relative polarity over a circuit which passes from terminal B, at signal 13S, through back point of contact 42 of relay 13DR, back point of contact 43 of relay 13HR, back point of contact 44 of relay 13PC, front contact 45 of track relay 6TR, front contact 46 of track relay 5TR, asymmetric unit A3, relay 12HR, asymmetric unit A, front contact 47 of track relay 5T, front contact 48 of track relay 6TR, back point of contact 49 of relay 13PC, back point of 15 contact 50 of relay 13HR, and back point of contact 51 of relay 13DR to terminal C.

When the line wires are energized with current of this relative polarity the relay 12DR is not energized since the asymmetric unit A1 prevents flow of current of this relative polarity in the winding of the relay 12DR. The contacts of relay 12DR, therefore, remain released.

When relay 12HR is energized and relay 12DR is deenergized by current of the opposite relative polarity, relay 11DR is energized over a circuit which passes from terminal B at signal 12 through front point of contact 53 of relay 12HR, back point of contact 54 of relay 12PC, front contact 55 of relay 5TR, front contact 56 of relay 3TR, asymmetric unit A2, relay 11DR, asymmetric unit A1, front contact 57 of relay 3TR, front contact 58 of relay 4TR, back point of contact 59 of relay 12PC, and front point of contact 60 of relay 12HR to terminal C.

When the line wires are energized with current of this relative polarity the relay 11HR is not energized since the asymmetric unit A prevents flow of current of this relative polarity in the winding of the relay. The contacts of the 40 relay 11HR, therefore, remain released.

When relay 11HR is deenergized and relay 11DR is energized, both relays 11PC and 11CT are energized over a circuit which passes from terminal B through normal polar contact 63-64 of relay 45 11DR, front contact 65 of relay 11DR, back point of contact 66 of relay 11HR, and thence over two paths, one of which passes through transfer relay 11PC to terminal C and the other of which passes through coding relay 11CT to terminal C. 50 When both relays 11PC and 11CT are energized, both relays 10HR and 10DR are energized by alternating current supplied over the line circuit for section W-X. That is, this line circuit is connected by front contacts 68 and 69 of relay 55 11PC to contacts 70 and 71 of coding relay 11CT so that the line circuit is alternately supplied with current of one polarity and then the other polarity.

When the line wires of the section W-X are supplied with current of one relative polarity, by the coding relay 11CT, the winding of relay 10HR is energized, while the asymmetric unit A1 prevents flow of this current in the winding of relay 10DR. Similarly when the line wires are supplied with current of the other relative polarity the winding of the relay 10DR is energized, while the asymmetric unit A prevents flow of this current in the winding of the relay 10HR.

On subsequent reversal of the polarity of the 70 current supplied by the coding relay 11CT to the line wires of the section W-X, the winding of relay 10HR is again energized, while the winding of relay 10DR is no longer energized.

The contacts of the relays 10HR and 10DR do 75

not release instantaneously on the interruption of the supply of current to the windings of these relays, and the reversals in the polarity of the current supplied by the coding relay 11CT are so rapid that the relays 10HR and 10DR bridge over the periods in which their windings are not energized, with the result that when the line wires are supplied with alternating current by the coding relay 11CT, the contacts of the relays 10HR and 10DR are maintained picked up.

When both relays 10HR and 10DR are energized, transfer relay 10PC and coding relay 10CT are both energized so that the line circuit for the signal (not shown) next in rear of signal 10S is supplied with alternating current to provide a "proceed" indication at that signal. The circuit for the energization of relay 10PC and relay 10CT may be traced from terminal B through normal polar contacts 72-73 of relay 10DR, front contact 74 of relay 10DR, normal polar contact 75-76 of relay 10HR, front point of contact 77 of relay 10HR, and thence over two paths, one through relay 10PC to terminal C, and the other through relay 10CT to terminal C.

It will be noted that the polar contacts of relays HR and DR do not ordinarily change their positions. That is, as long as the associated asymmetric units function properly, the relays HR and DR will maintain their normal polar contacts closed when energized. However, if, for example, the asymmetric units at signal 12S should become deranged so that relay 12DR should become energized by the current which is energizing relay 12HR, the neutral contacts of relay 12HR would become picked up and the polar contacts of relay 12DR would immediately assume their reverse position since such current is of reverse polarity with respect to relay 12DR. The picking up of the neutral contacts and the reversal of the polar contacts of relay 12DR would light the yellow lamp Y of the top unit T of signal 12S by a circuit which passes from terminal B through front point of contact 19 of relay 10DR, reverse polar contact 80-81, and lamp Y to terminal C; and would light also the red lamp R of the lower unit L over a circuit which passes from terminal B through front point of contact 21 of relay 12DR, reverse polar contact 82-83, and lamp R to terminal C. The signal 12S, therefore, would continue to display a yellow light over a red light and would be prevented from displaying a less restrictive indication even though relays 12HR and 12DR are both energized. Similarly, if the asymmetric units at signal 11S should become deranged so that relay 11HR should become energized by the current which is energizing relay 11DR, the neutral contacts of relay 11HR would become picked up and the polar contacts of relay 11HR would immediately reverse their position. The picking up of the neutral contacts and the reversal of the polar contacts of relay 11HR would light the yellow lamp Y of the top unit T at signal 11S by a circuit which passes from terminal B through front point of contact 22 of relay 11DR, normal polar contact 23-24 of relay 11DR, front point of contact 25 of relay 11HR, reverse polar contact 84-85 of relay 11HR, and lamp Y to terminal C; and the red lamp R of the lower unit L would be lighted by a circuit which passes from terminal B through front point of contact 26 of relay 11DR, normal polar contact 27-28 of relay 11DR, front point of contact 29 of relay 11HR, and lamp R to terminal C. The signal 11S would display a yellow light over a red light instead of

a yellow light over a green light; that is, a more restrictive indication, even though relays 11HR and 11DR are both energized.

It will be noted that if relay 11HR should become energized by current of such polarity as is required to energize relay 11DR, the circuit for the energization of relay 11PC and relay 11CT will become opened by the reversal of polar contact 86 of relay 11HR so that the line circuit for the signal 10S will be supplied with direct current of such polarity as will pick up relay 10HR. The signal 10S, therefore, will display a more restrictive indication, that is, a yellow light over a green light instead of a green light over a red light.

Referring next to Fig. 2, the reference character PO with a suitable distinguishing prefix designates an alternating current transfer relay which may be used at each signal instead of the transfer relay PC shown in Figs. 1A and 1B.

With the modification shown in Fig. 2, the coding relay CT at each signal is replaced by a source of alternating current the terminals of which are designated by the reference characters BX and CX. The source of alternating current, for example, may be any convenient commercial supply.

It will be apparent that the relays PO operate in a manner similar to that described for the relays PC shown in Figs. 1A and 1B. That is, when the relays PO are energized, the line circuits for the signals next in rear are supplied with alternating current and when the relays PO are deenergized, such line circuits are supplied with direct current of one polarity or another depending upon traffic conditions in advance.

For example, at signal 11S, the transfer relay 11PO may be energized by a circuit which passes from terminal BX through normal polar contact 90-91 of relay 11DR, front contact 92 of relay 11DR, back point of contact 93 of relay 11HR, and relay 11PO to terminal CX. When relay 11PO is energized, the line circuit for the control of relays 10HR and 10DR is connected to alternating current by the front points of contacts 94 and 95 of relay 11PO so that signal 10S will display the "proceed at normal speed" indication. When relays 10HR and 10DR are both energized, the relay 10PO is energized by a circuit which passes from terminal BX through normal polar contact 94-95 of relay 10DR, front contact 96 of relay 10DR, normal polar contact 97-98 of relay 10HR, front point of contact 99 of relay 10HR, and relay 10PO to terminal CX. When relay 10PO is energized, the line circuit for the signal next in rear is supplied with alternating current energy over the front points of contacts 100 and 101 of relay PO so that such signal is caused to display the "proceed at normal speed" indication.

It will be apparent that with the modification shown in Fig. 2, if the alternating current source of energy should fail, the system will continue to function as a two-block, three-indication system, to keep traffic moving. For example, if the alternating current source should fail at signal 11S, the relay 11PO would become released so that direct current energy of the polarity effective to energize relay 10DR would be supplied to the line circuit for the signal 10S.

Although I have shown in Fig. 2 a portion of the apparatus associated with signals 10S and 11S only, it is understood that this modification may be applied to each signal shown in Figs. 1A and 1B, and that when the system is modified as illus-

trated in Fig. 2, the signaling system operates in a manner similar to that described for the system shown in Figs. 1A and 1B except where shown and described otherwise. In other words, my invention 5 comprises a signaling system which may convert its supply of alternating current from the usual source of direct current at each signal, or which may receive its supply of alternating current from a source separate and distinct from its 10 usual direct current source of energy.

Referring now to Fig. 3, the reference character Q designates in general an alternator which may be substituted for the current coding relay CT. As here shown, alternator Q is of the well-known 15 tuned reed type having an elastic member 103 which is caused to vibrate between terminals 104 and 105 by a control winding 106. In the deenergized condition, member 103 does not connect with either terminal 104 or 105 but does connect 20 with a terminal 107. When energy is supplied to alternator Q, winding 106 will attract member 103 causing it to connect with terminal 105 and to move away from terminal 107, causing winding 106 to become deenergized. Upon the deenergization 25 of winding 106, the resilience of member 103 will cause it to move away from terminal 105 and to connect with terminal 104 as well as with terminal 107. The circuit for winding 106 being then again completed through terminal 107, winding 106 will again attract member 103 causing the 30 cycle of operation just described to be repeated. Winding 106 will then be repeatedly energized and deenergized as long as energy is supplied to its control circuit.

When member 103 connects with terminal 105, 35 current is supplied to the right-hand portion of the primary winding 108 of a transformer F, and when member 103 connects with terminal 104, current is supplied in the opposite direction to the 40 left-hand portion of primary winding 108 of transformer T. Alternating current, therefore, is induced in the secondary winding 109 of transformer F.

The secondary winding 109 is connected to the 45 line circuit for the section next in rear over front contacts of the relay PC, and winding 106 of alternator Q is controlled by the associated relays HR and DR in a manner similar to that described for the coding relay CT. That is, alternator Q operates to supply alternating current to the line circuit for the section next in rear whenever the 50 associated relay DR is energized provided the associated relay HR is deenergized or is energized by current of the proper polarity. In other words, the alternator Q functions to supply alternating 55 current in a manner similar to that described for coding relay CT and, if desired, may be substituted for relay CT at any or all of the signals shown in Figs. 1A and 1B. For example, the alternator Q 60 may be substituted for the relay 10CT at signal 10S in Fig. 1A by connecting secondary 109 of transformer F to wires 110 and 111 and by connecting member 103 to wire 112 and winding 106 to terminal C.

From the foregoing description, it will be apparent 65 that I have provided a simple and reliable system of three-block, four-indication, signaling utilizing asymmetric units for securing the different proceed indications over two line wires 70 wherein the signals of the system are prevented from displaying a less restrictive indication, and in some cases are caused to display a more restrictive indication, in the event of a failure of the asymmetric units to function properly. Furthermore, 75 in the event of failure of the alternating

current source of energy in the modification utilizing a separate source of alternating current, my system continues to operate as a two-block, three-indication, system.

Although I have herein shown and described 5 only a few forms of apparatus embodying my invention, it is understood that various changes and modifications may be made therein within the scope of the appended claims without departing from the spirit and scope of my invention. 10

Having thus described my invention, what I claim is:

1. In combination, a section of railway track, a pair of conductors for said section governed by traffic conditions in said section, two signal control relays receiving energy from said conductors, means including asymmetric units for causing said two relays to assume one condition when said conductors are supplied with direct current and for causing said two relays to assume a different condition when said conductors are supplied with alternating current, a source of alternating current and a source of direct current, and another relay controlled by said source of alternating current for connecting said conductors with said direct current source when said alternating current is absent.

2. In combination, a section of railway track, a pair of conductors for said section governed by traffic conditions in said section, two signal control relays receiving energy from said conductors, means including asymmetric units for causing said two relays to assume one condition when said conductors are supplied with direct current and for causing said two relays to assume a different condition when said conductors are supplied with alternating current, a source of alternating current and a source of direct current, and another relay controlled by said source of alternating current as well as by traffic conditions in advance of 40 said section for connecting said direct current source or said alternating current source with said conductors.

3. In combination, a section of railway track, a pair of conductors for said section governed by 45 traffic conditions in said section, two signal control relays receiving energy from said conductors, means including asymmetric units for causing said two relays to assume one condition when said conductors are supplied with direct current 50 and for causing said two relays to assume a different condition when said conductors are supplied with alternating current, a source of alternating current and a source of direct current, and another relay controlled in accordance with 55 traffic conditions in advance of said section for connecting said conductors either with said direct current source or said alternating current source but not both simultaneously.

4. In combination, a section of railway track, 60 a pair of conductors for said section controlled by traffic conditions in said section, means for reversibly supplying current to said conductors, two polarized relays connected to said conductors, asymmetric units associated with said relays 65 for permitting current of one polarity but not of the other to pass through one relay and for permitting current of the second polarity but not of the first to pass through the other relay, a signal for said section capable of displaying a 70 plurality of proceed aspects, circuit means including neutral and polar contacts of said relays for controlling the different aspects of said signal, and means including polar contacts of said relays for preventing the display of a less re- 75

strictive aspect by said signal in the event said asymmetric units fail to function properly.

5. In combination, a section of railway track, a pair of conductors for said section controlled by traffic conditions in said section, means for reversibly supplying current to said conductors, two polarized relays connected to said conductors, asymmetric units associated with said relays for permitting current of one polarity but not 10 of the other to pass through one relay and for permitting current of the second polarity but not of the first to pass through the other relay, a signal for said section capable of displaying a plurality of proceed aspects, circuit means including neutral and polar contacts of said relays 15 for controlling the different aspects of said signal, and means including polar contacts of said relays for causing the display of a more restrictive aspect by said signal in the event said asymmetric units fail to function properly.

6. In combination, a section of railway track, a pair of conductors for said section controlled by traffic conditions in said section, means for reversibly supplying current to said conductors, two polarized relays connected to said conductors, asymmetric units associated with said relays for permitting current of one polarity but not 20 of the other to pass through one relay and for permitting current of the second polarity but not of the first to pass through the other relay, signal means for said section controlled by said relays, and means including neutral and polar contacts of said relays for controlling the supply of current to the conductors for the section next 25 in rear.

7. In combination, a section of railway track, a pair of conductors for said section controlled by traffic conditions in said section, means for reversibly supplying current to said conductors, two polarized relays connected to said conductors, asymmetric units associated with said relays for permitting current of one polarity but not 30 of the other to pass through one relay and for permitting current of the second polarity but not of the first to pass through the other relay, signal means for said section controlled by said relays, other signal means controlled by another pair of conductors, and means including polar contacts of said relays for controlling the supply 35 of current to said other conductors whereby if said asymmetric units fail to function properly said other conductors are supplied with current of such character as to cause said other signal means to display a more restrictive indication.

8. A railway signal system comprising a stretch of railway track divided into blocks, a pair of conductors for each block controlled by traffic conditions in that block, two relays for each block and each relay receiving energy from the associated conductors, asymmetric units associated with the relays for each block for permitting current of one polarity but not of the other to pass through one relay and for permitting current of the second polarity but not of the first to pass 40 through the other relay, means for supplying current of one polarity or current of the other polarity or alternating current to each pair of conductors in accordance with traffic conditions in advance of the associated block; and a signal for each block controlled by the relays for that section and arranged to have a first aspect when both relays are deenergized, a second aspect when one relay is energized, a third aspect when the other relay is energized, and a fourth aspect when both relays are energized.

9. In combination, a section of railway track, a pair of conductors for said section governed by traffic conditions in said section, a signal controlled by said conductors and arranged to display its least restrictive aspect when said conductors are supplied with alternating current, a source of direct current, a device operative when energized to convert direct current to alternating current, and means governed by traffic conditions in advance of said section for supplying current to energize said device and for connecting said device to said conductors thereby supplying the conductors with alternating current.

10. In combination, a section of railway track, a first relay and a second relay each having neutral and polar contacts, means effective to deenergize both relays when said section is occupied, means effective when said section is unoccupied for energizing only the first relay in the normal direction or only the second relay in the normal 15 direction or both relays in the normal direction in accordance with traffic conditions in advance of said section, a signal for said section including a first unit comprising a stop and a caution as well as a proceed lamp and a second unit comprising a stop and a proceed lamp, a circuit for the stop lamp of the first unit including a back contact of both relays, a circuit for the stop lamp of the second unit including a back contact of said second relay, a circuit for the caution lamp of the first unit including a front contact of said first relay and a back contact of said second relay, another circuit for said caution lamp including a back contact of said first relay as well as a front contact and a normal polar contact 20 of said second relay, a circuit for the proceed lamp of said second unit including a back contact of said first relay as well as a front contact and a normal polar contact of said second relay, and a circuit for the proceed lamp of said first unit including a front contact and a normal polar contact of said first relay as well as a front contact and a normal polar contact of said second relay.

11. In combination, a section of railway track, a first relay and a second relay each having neutral and polar contacts, means effective to deenergize both relays when said section is occupied, means effective when said section is unoccupied for energizing only the first relay in the 25 normal direction or only the second relay in the normal direction or both relays in the normal direction in accordance with traffic conditions in advance of said section, a signal for said section including a first unit comprising a stop and a caution as well as a proceed lamp and a second unit comprising a stop and a proceed lamp, circuits for said lamps controlled by said first and second relays whereby said signal is caused to display a stop and three distinctive proceed indications respectively, an auxiliary circuit for the caution lamp of the first unit including a reverse polar contact of said second relay, another auxiliary circuit for said caution lamp including a reverse polar contact of said first relay, and an auxiliary circuit for the stop lamp of said second unit including a reverse polar contact of said second relay, said auxiliary circuit being effective at times to provide a restrictive indication in the event said first and second relays become energized in the reverse direction.

12. In combination, a forward and a rear section of railway track, a first and a second relay each having neutral and polar contacts associated with said forward section, means for energizing 30

only said first relay in the normal direction or 5 only said second relay in the normal direction or both relays in the normal direction according to traffic conditions in advance of said forward section, a pair of conductors for the rear section, an auxiliary relay effective to connect said conductors with a source of alternating current or a source of reversible direct current according as the auxiliary relay is energized or deenergized 10 respectively, a circuit for said auxiliary relay including a back contact of said first relay as well as a front contact and a normal polar contact of said second relay, and another circuit for said auxiliary relay including a front contact and a normal polar contact of said first relay as well 15 as a front contact and a normal polar contact of said second relay.

13. In combination, a forward and a rear section of railway track, a first and a second relay 20 each having neutral and polar contacts associated with said forward section, means for energizing only said first relay in the normal direction or only said second relay in the normal direction or both relays in the normal direction 25 according to traffic conditions in advance of said forward section, a pair of conductors for the rear section, a device for converting direct current to alternating current, a circuit for supplying said device with direct current including a front contact and a normal polar contact of said first relay as well as a front contact and a normal polar contact of said second relay, another circuit for 30 supplying said device with direct current including a back contact of said first relay as well as a front contact and a normal polar contact of said second relay, and means controlled by said first and second relays for supplying said conductors with alternating current from said device. 35

14. In combination with a section of railway 40 track, a control circuit, a source of direct current, a device having contacts which are operative when the device is energized to convert direct current into alternating current, means governed by traffic conditions in advance of said section for at times connecting said control circuit to the contacts of said device and for at such times connecting said device to said source of direct current to thereby energize said device, whereby said control circuit is supplied at such 45 times with alternating current, and traffic governing means for said section receiving energy from said control circuit and responsive uniquely to alternating current.

15. In combination with a section of railway 50 track, a control circuit, a source of direct current, a device having contacts which are operative when the device is energized to convert direct current into alternating current, means governed by traffic conditions in advance of said section for at times connecting said control circuit to the contacts of said device and for at such times connecting said device to said source of direct current to thereby energize said device, whereby said control circuit is supplied at such times with 55 alternating current, means also governed by traffic conditions in advance of said section for selectively supplying said control circuit with direct current from said source, and traffic governing means for said section receiving energy from said control circuit and selectively responsive to direct current and alternating current.

16. In combination, a section of railway track, a pair of conductors for said section governed by traffic conditions in said section, means for supplying said pair of conductors with current in 75

one direction or the other in accordance with traffic conditions in advance of said section, two relays receiving energy from said pair of conductors, asymmetric units associated with said relays for permitting current of one polarity but not of the other supplied from said conductors to pass through one relay and for permitting current of the second polarity but not of the first supplied from said conductors to pass through the other relay, a signal for said section governed by said two relays, said signal being capable of displaying a clear indication and a plurality of different restrictive proceed indications, and means governed by said two relays for causing said signal to display a restrictive proceed indication in the event said asymmetric units fail to function properly. 10 15

17. In combination, a section of railway track, a pair of conductors for said section governed by traffic conditions in said section, means for supplying said pair of conductors with direct current in one direction or the other or with alternating current in accordance with traffic conditions in advance of said section, two polarized relays receiving energy from said pair of conductors, asymmetric units associated with said relays for permitting current of one polarity but not of the other supplied from said conductors to pass through one relay and for permitting current of the second polarity but not of the first supplied from said conductors to pass through the other relay, a signal for said section controlled by said two relays, said signal being capable of displaying a clear indication and a plurality of different restrictive proceed indications, and means governed by said two relays for causing said signal to display a restrictive proceed indication in the event said asymmetric units fail to function properly. 20 25 30

18. In combination, a stretch of railway track divided into a plurality of successive block sections, a signal for each section capable of providing a stop indication and a plurality of different proceed indications, each section having a pair of conductors governed by traffic conditions in said section and electroresponsive means energized from said conductors, said electroresponsive means assuming one condition when not energized, a second condition when supplied only with unidirectional current of one relative polarity, a third condition when supplied only with unidirectional current of the other relative polarity, and a fourth condition when supplied with alternating current, each section also having associated therewith a supply device operative on the supply of direct current thereto to convert said direct current into alternating current and to supply such alternating current to a circuit through which current may be supplied to the conductors of the adjacent block section in the rear, the electroresponsive means for each section being selectively operative in accordance with its condition to control the signal for such section, the supply of direct current to the supply device for such section, and the polarity of the unidirectional current supplied to the conductors of the adjacent block section in the rear. 40 45 50 55 60 65

19. In combination with a section of railway track, a control circuit, a source of direct current, a supply device having contacts, said supply device being operative when and only when said contacts are operated to convert direct current into alternating current which may be supplied to said control circuit, the contacts of said supply device being operated when and only when direct current is supplied to said device, means con- 70 75

trolled by traffic conditions in advance of said section for at times supplying direct current to said supply device to thereby effect the supply of alternating current to said control circuit, and traffic governing means for said section receiving energy from said control circuit and responsive uniquely to alternating current.

20. In combination, a stretch of railway track divided into a plurality of successive block sections, a signal for each section capable of providing a stop indication and a plurality of different proceed indications, each section having a pair of conductors governed by traffic conditions in said section, each section also having electroresponsive control means energized from the conductors for such section and controlling the signal for such section, each section having a supply device having contacts, said device being operative only when said contacts are operated to convert direct current into alternating current which may be supplied to the conductors of the adjacent section in the rear, the contacts of said device being operated only when direct current is supplied to said device, the control means for each section assuming one condition when deenergized, a different condition when supplied with direct current and a still different condition when supplied with alternating current, the control means for each section being selectively operative in accordance with its condition to control the signal for the section with which said control means is associated, to at times effect the supply of direct current to the supply device for such section, and to also control the supply of direct current to the conductors of the adjacent block section in the rear.

21. In combination, a stretch of railway track divided into a plurality of successive block sections, a signal for each section capable of providing a stop indication and a plurality of different proceed indications, each signal having associated therewith electroresponsive control means and controlling the signal, each signal having associated therewith a supply device having

contacts, said supply device being operative only when said contacts are operated to convert direct current into alternating current which may be supplied to the electroresponsive means associated with the adjacent signal in the rear, the contacts of said supply device being operated only when direct current is supplied to said device, the control means associated with each signal assuming one condition when deenergized, a different condition when supplied with unidirectional current and a still different condition when supplied with alternating current, the control means associated with each signal being selectively operative in accordance with its condition to control the signal with which it is associated, to at times effect the supply of direct current to the supply device associated therewith, and to also control means for supplying unidirectional current to the control means associated with the adjacent signal in the rear.

22. In combination, a section of railway track, a pair of conductors for said section governed by traffic conditions in said section, means for supplying said pair of conductors with current of one polarity or the other in accordance with traffic conditions in advance of said section, two relays receiving energy from said pair of conductors, asymmetric units associated with said relays for permitting current of one polarity but not of the other supplied from said conductors to pass through the winding of one relay and for permitting current of the other polarity but not of the first supplied from said conductors to flow through the winding of the other relay, a signal for said section governed by said two relays, said signal being capable of displaying a clear indication and a plurality of different restrictive proceed indications, and means governed by said two relays and operative in the event said asymmetric units fail to function properly to condition the signal to display a proceed indication at least as restrictive as that which would be displayed if the asymmetric units were functioning properly.

HENRY S. YOUNG.
